United States Patent [19]

Idowu et al.

[11] Patent Number: Des. 317,503

[45] Date of Patent: ** Jun. 11, 1991

[54] **ENDOTRACHEAL TUBE WITH AN INFLATABLE SUCKING DEVICE**

[76] Inventors: **Olajire Idowu**, 1734 Mettler Rd., Lodi, Calif. 95242; **Karen H. Sousa**, 3135 Seagull La., Stockton, Calif. 95209

[**] Term: **14 Years**

[21] Appl. No.: **274,133**

[22] Filed: **Nov. 21, 1988**

[52] U.S. Cl. **D24/115; D24/111**
